HOUSE-WIRING APPARATUS.

1,305,968.

Specification of Letters Patent. Patented June 3, 1919.

Application filed June 29, 1916. Serial No. 106,711.

To all whom it may concern:
Be it known that I, GILBERT H. INMAN, a citizen of the United States, residing at Taunton, in the county of Bristol and State of Massachusetts, have invented certain new and useful Improvements in House-Wiring Apparatus; and I do hereby declare the following to be a full, clear, and exact description of the invention, such as will enable others skilled in the art to which it appertains to make and use the same.

The present invention relates to house wiring apparatus.

The object of the invention is to produce an apparatus by the use of which the laying of telephone, light, and other electric wires in finished buildings may be neatly and expeditiously performed without the necessity of taking up floorings or otherwise defacing the rooms of the building. It is desirable that electric wires be laid between the floors and ceilings and between partition walls so as to avoid the unsightly appearance of electric wire moldings. When the wires are to be laid longitudinally of the beams which support the flooring, the problem presented is comparatively simple; but when the wires must be laid transversely of the beams, as is often the case, a problem of considerable difficulty is presented. It is readily seen that when a building is finished it is practically impossible to lay wires in this latter manner except by taking up a portion of the flooring and boring through each beam separately. To remove the flooring of the finished building is not only expensive, in that it entails considerable work, but undesirable because the floors can almost never be replaced in the same condition in which they were originally laid. By means of the wiring apparatus of the present invention electric wires may be laid in any finished building without the necessity of removing the flooring in any of the living rooms or in the rooms where it is undesirable that the flooring should be disturbed. Although applicable for use in wiring buildings of any description, the apparatus of the present invention is particularly adapted for the wiring of residences where it is only permissible to remove the flooring of closets or other out of the way places. To the accomplishment of the above object, the invention consists

in the house wiring apparatus hereinafter described and particularly pointed out in the appended claims.

In the accompanying drawings illustrating the preferred form of the invention, Figure 1 is a side elevation of the house wiring apparatus showing it in position for use; Fig. 2 is a front elevation of one of the swivel blocks and of the indicating device; Fig. 3 is a section, taken on the line 3—3 of Fig. 1; Fig. 4 is a plan of the apparatus; Fig. 5 is a perspective view, with the middle portion broken away, of one of the extension joints; Fig. 6 is a similar view showing the extension joint locked to the bit holder, which is shown in section; Figs. 7 and 8 are respectively perspective views of the pilot and of the bit holder, Fig. 9 is a perspective view, with the middle portion broken out, of the locking tube; and Fig. 10 is a perspective view of the key for locking and unlocking the locking tube.

The house wiring apparatus illustrated in the drawings comprises a boring machine, generally indicated at 10, through which power is transmitted to impel the bit 11 through the beams of the house or building to be wired. The bit may be an ordinary Russell-Jennings bit with a machine threaded shank for use in boring holes in wood, or it may be a Syracuse bit such as is ordinarily used for cutting through nails. The boring machine 10 is provided with a spindle 12 journaled in the lower ends of supports 13 depending from a plate or table 14. A web 15 serves to hold the supports 13 rigidly connected. Secured to the spindle 12 is a bevel gear 17 which meshes with a bevel pinion 18 secured to the lower end of a vertically disposed driving shaft 19 journaled in the web 15 and in the table 14. A collar 20 secured to the shaft 19 above the web 15 holds the shaft from end play. Rotary movements are imparted to the shaft, in order to turn the bit 11, by means of a handle 21 loosely received on a stud secured to the end of a crank web 22 which fits on to the squared upper end of the shaft 19 and is secured thereon by a nut 23. The crank web 22 is provided with two extra squared holes 24 so that it may be turned in localities too narrow for the swing of the handle when in the position shown in the

drawings. Mounted on the shaft 19 immediately below the web 22 is an ordinary bit stock ratchet 25. As the operator using the apparatus turns the handle 21 with one hand, with the other he grasps a feed handle 26 by which he pushes the boring machine and thereby feeds the bit into the beams to be bored. The handle 26 loosely embraces the part of the shaft 19 extending upwardly from the table 14, and is secured at its lower end to the table. The table 14 is provided with two guideways which rest upon two guide bars 28. These guide bars are of sufficient length to bridge the space separating two adjacent beams. They are formed of square tubing and are loosely received in square holes in swivel blocks 30 and 31. The swivel blocks 30 and 31 are pivotally supported on plates or bases 32 and 33 respectively, which are provided with holes for wood screws 29, by which the bases may be secured to two adjacent beams, 34 and 35. When the wires are to be laid at right angles to the beams, and the beams to be bored lie to the right of the beams shown in Figs. 1 and 4, the plate 33 is secured to the top of the beam 35 longitudinally thereof. The guide bars 28 are adjusted in the swivel block 31 so that their right hand ends are about flush with the front side thereof; thereupon the guide bars are secured in the swivel block 31 by means of the setscrews 36. The plate 32 and swivel block 30 are then slid along the guide bars away from the swivel block 31 until the plate 32 is about over the median line of the beam 34, whereupon the guide bars are secured in the swivel block 30 by tightening upon the thumb screws 37. The plate 32 is then adjusted longitudinally of the beam 34 until the guide bars are at right angles to the beams. The plate 32 is then fastened to the beam 34 and the swivel block 30 is secured to the plate by tightening on the thumb screw 38. The plates, blocks, and guide bars are thus held in rigid connection.

The boring machine is next placed on the guide bars 28 with the bit 11 directed toward the beam 35. The boring machine is held in operative position on the guide bars by means of a lever 39 located beneath the table 14 and pivoted thereto at 40. A contraction spring 41 secured at one end to the free end of the lever 39 and secured at the other end to a pin 42 projecting from the table 14, tends to swing the lever 39 inwardly toward the center of the machine and away from the guide bar to which it is adjacent. When the machine has been placed in operative position on the guide bars, as shown in the drawings, the lever is swung under the adjacent guide bar by means of a cam piece 44 pivoted beneath the table at 45. Secured to the upper end of the pivot pin 45 is a handle

46. By swinging the handle 46 outwardly from the center of the table, the cam piece 44 is moved against the lever 39 and forces it under the adjacent guide bar, thereby preventing the boring machine from upward displacement. The end of the cam 44 is received in a notch in the lever 39 and thereby held in outward position. By turning the handle 46 toward the center of the machine, the cam 44 is disengaged from the notch in the lever 39 and the spring 41 acts to draw the lever from under the guide bar so that the machine can be lifted from the bars. When the lever 39 is in operative position under its adjacent guide bar, the boring machine may be slid freely along on the bars 28.

If circumstances require that the wires be laid obliquely across the beams of the house, the apparatus may be adjusted so that it will bore a hole obliquely across the beams. In positioning the apparatus for boring an oblique hole, the plate 33 is first adjusted to the beam 35 longitudinally thereof, the guide bars 28 being secured in the swivel block 31 as before. The plate 32 and the swivel block 30 are then slid along on the guide bars until the adjacent beam 34 is reached. Thereupon, the plate 32 is moved longitudinally of the beam 34 in either direction according to the direction in which the hole is to be bored. The movement of the plate 32 along the beam 34 is continued until a pointer or needle 48 registers with the proper graduation on a dial plate 49. It is assumed that the hole to be bored is the hypotenuse of a right angle triangle, the longer leg of which is 10 feet transversely of the beams and the shorter leg of which is 5 feet longitudinally of the beams. The plate 32 is adjusted longitudinally of the beam 34 in either direction until the pointer 48 registers with, say, one of the figures 10 on the dial plate 49. The graduations, of course, correspond to the sine values of the angular relation of the hole to be bored to a straight line at right angles to the beam 35 to which the plate 33 is attached.

The pointer 48 is secured to the upper end of a vertically disposed shaft 50 journaled in the dial plate 49 and in a bearing block 51 secured to the swivel block 31. The dial plate 49 is supported on the swivel block 31 by an upright 52 and by an ear 53 extending laterally of the dial plate, which surrounds the upper end of the pivot pin 54, by which the swivel block 31 is connected with the plate 33. Fastened on the shaft 50 is a pinion 55 which meshes with a gear 56 secured to the upper end of the pivot pin 54. The pivot pin 54 is fixed in the plate 33 and is loosely received in the swivel block 31. By means of this construction, when the plate 32 is moved along the beam 34 the swivel block 31 is caused to swing about the

pivot pin 54, and at the same time the pinion 55 travels around the periphery of the gear 56, which causes the pointer 48 to indicate the amount of angular displacement between 5 the block 31 and the plate 33. When the swivel block 31, and consequently the guide bars 28, have been swung to the proper angular relation with the plate 33, and therefore with the beam 35, as indicated by the 10 pointer 48, the plate 32 is secured to the beam 34 as before, the pivotal connection between the swivel block 30 and the plate 32 permitting angular movement between them. The swivel block 30 is then secured 15 to the plate 32, as before, by tightening on the thumb screw 38. The thumb screws 37 are also tightened on the guide bars. The hole is then bored in the same manner as though it were a hole at right angles across 20 the beams rather than obliquely across them.

As shown in the illustrated embodiment of the invention, the travel of the boring machine is limited to the amount of space between two adjacent beams, so that when 25 the first beam has been bored it is obvious that the shank of the bit will not be long enough to permit it to be used in boring the next beam, and that, consequently, means must be provided for extending the bit to 30 the next and to subsequent beams until the desired point is reached. For this purpose a series of extension joints are provided. Each extension joint consists of three parts, 35 an outer shell or driving member 58, an intermediary or guide member 59, and an innermost or locking member 60. The guide member 59 is fixed in the driving member 58, and the locking member 60 is loosely received in the guide member 59. The exterior 40 surface of the driving member is smooth, and its ends are rabbeted to provide interlocking driving joints. By an inspection of Fig. 5 it will be seen that the left hand end (viewing Fig. 5) or shank end 61 of the 45 guide member 59 projects outwardly beyond the driving member 58, and at its other end it terminates at an equal distance within the opposite or forward end of the driving member 58. The ends of the guide member 50 are also rabbeted, as shown, and the shank end is provided with an inturned lug 62. The shank 61 of the guide member 59 is 55 slightly smaller in diameter than the inside diameter of the part of the driving member 58 which projects beyond the forward end of the guide member 59. When a series of extension joints are joined together and locked, the shanks of the guide members are inserted into the forward ends of the driving members. When the guide shank of one extension joint has been thus inserted into the forward end of the driving member of another extension joint, so that the rabbeted ends of the respective members overlap, the 60 locking member 60 is rotated by turning an 65 outturned lug 63 thereof which bears against the adjacent outer end of the guide member, until a slot 64 formed in the opposite end of the locking member engages the lug 62. When the slot 64 has engaged the 70 lug 62, the lug 63 is received in a slot 65 formed in the shank of the guide member. The two extension pieces are thus securely locked together. By locking together a series of the extension joints, beams at a considerable distance from the boring machine may be reached and bored. The shanks of the guide members are of such length and their fit in the forward ends of the driving members is such that when the joints are 75 locked together they are in perfect alignment, thereby forming a straight and smooth extension shank for the bit.

When the apparatus has been placed in position to bore the first beam, the shank 67 80 of the guide member 68 of the bit holder 69 is inserted into a collet 70. The collet 70 is secured to the spindle 12, shown in Fig. 1. The outside diameter of the collet 70 is the same as the outside diameter of the driving 85 members of the extension joints, and the inside diameter of the collet is slightly larger than the outside diameter of the shanks of the guide members of the extension joints. The outer or forward end of the collet is 90 rabbeted at 71. It is not necessary that the shank 67 of the bit holder or that the shanks of the extension joints be locked in the collet 70 because the collet is used only to turn the bit and feed it through the beams and is not 95 used in withdrawing the bit or the extension joints from the bored holes. The bit holder 69 is provided with a threaded hole into which the bit is screwed. When the first beam has been bored, the bit is left in the 100 beam and the boring machine is pulled back therefrom, so that the collet is disengaged from the shank of the bit holder. One of the extension joints is then interposed between the bit and the collet. The front end 105 of the extension piece is fitted over the shank of the bit holder so that the forward end of its driving member overlaps the rabbeted part 72 of the bit holder. The locking member 60 is then turned until the slot 64 therein 110 engages with the lug 73 of the shank 67 of the guide member of the bit holder. This lug 73 corresponds to the lug 62 of the extension joint. The extension joint is thus locked to the bit holder. The shank of the 115 guide member of the extension joint is then inserted in the collet 70, and the driving portion 74 of the latter is made to overlap with the driving portion of the extension joint. Thereupon, the boring machine is 120 pushed toward the beam 35 until the bit 11 encounters the next beam, which is then bored. When a hole has been bored in this beam also, the bit is left therein and the machine is pulled back toward the beam 34 as 125 130

before, leaving the shank of the extension joint projecting from the first beam bored, that is, the beam 35. Thereupon, another extension joint is locked to the extension joint connected with the bit holder 69, and the boring operation is continued as before. As the successive beams are bored, additional extension joints are interposed between the last extension joint and the collar 70.

In order to facilitate the turning of the locking member 60 in the guide member 59, in locking the parts together, a wrench 76 is employed. The forward end of the wrench is provided with a teat 77 of slightly smaller diameter than the inside diameter of the locking member. Situated rearwardly of the teat is a collar 78, of slightly smaller diameter than the inside diameter of the guide member, which determines the operative position of the wrench when in engagement with the locking member. A slot 79 is cut through the collar and the teat. In use the wrench is inserted into the shank end of the guide member, the slot 79 enabling the teat and collar to pass the lug 62. When the teat 77 is wholly in the locking member with the collar against the end of the locking member and the slotted part of the collar engaging the lug 63, the wrench is turned until the slot 64 engages the lug 73 of the bit holder or the lug 62 of the next forward extension joint. A reverse movement of the wrench unlocks the parts.

When the requisite number of beams have been bored through, the handle 46 is turned to disengage the cam piece 44 from the notch in the lever 39, and the boring machine is lifted from the guide bars 28. The extension joints are then unlocked and removed one by one. After the extension joints and the bit have been removed from the hole, a pilot piece 80, shown in Fig. 7, is inserted in the hole in the first beam. The pilot piece is in every respect like the bit holder, except that at its forward end instead of being provided with a threaded hole for the reception of the bit, it is slightly tapered so that it may be readily guided into the holes in the beams, as shown in Fig. 7. The extension joints are then joined to the pilot piece one by one in the same manner in which they were joined to the bit holder to form the extended shank thereof. As each extension joint is locked to the preceding joint, the interlocked joints are pushed forward, the pilot readily finding the hole in the next beam because of the perfect alinement of the joints one with another. When the pilot has penetrated the last beam, a flexible wire rod or "snake," such as is used in drawing electric wires through holes or apertures, is put through the continuous hole which exists throughout the length of the interlocked joints. When the snake wire has been thus

put through, the extension joints are pulled out and unlocked one by one as before, leaving in their place throughout the holes in the beams the snake wire. The telephone or other electric wire to be laid is then secured to the rear end of the snake, and the other end of the snake which projected through the nose of the pilot is grasped and the snake and attached wires are drawn through the holes in the beams to the outlet. It is thus seen that the house wiring apparatus of the present invention affords a highly efficacious device by which electric wires may be laid in finished buildings where it is not permissible to remove the flooring except from a very narrow space such, for example, as a closet, where the removal of the flooring is permissible.

Having thus indicated the nature and scope of the present invention and having described a specific embodiment of the same, what is claimed is:

1. An apparatus for use in house wiring having, in combination, a boring machine, means for slidably supporting the machine between two adjacent beams, and an angle indicating device connected with the machine supporting means having provision whereby the angular displacement of holes to be bored obliquely to the beams may be determined, a bit, and an extension joint connecting the bit with the machine whereby succeeding beams may be reached and bored.

2. An apparatus for use in wiring houses having, in combination, plates adapted to be secured to adjacent beams, swivel blocks pivotally connected with the plates, guide bars loosely received in the blocks and bridging the space between the beams, a boring machine supported on the bars, a bit, and an extension shank connecting the bit with the machine consisting of a series of interlocked joints of uniform diameter less than the diameter of the bit.

3. An apparatus for use in wiring houses having, in combination, two plates adapted to be secured to two adjacent beams respectively, a swivel block pivotally connected with each plate, a gear mounted on the pivot pin of one plate, a pinion meshing with the gear, a pointer connected with the pinion, a dial plate, guide bars connecting the swivel blocks, a boring machine slidably supported thereon, a bit, and a shank interposed between the bit and the machine consisting of a series of interlocked joints.

4. An apparatus for use in wiring houses having, in combination, a boring machine, a bit, means for slidably supporting the machine between two adjacent beams, means connected with the supporting means for indicating the sine value of the angle between the hole to be bored and a straight line drawn through the longitudinal axis of the bit and at right angles to the beams, and ex-

tension joints connecting the bit with the boring machine so that succeeding beams may be bored.

5. An apparatus for use in house wiring, having in combination, a boring machine arranged to be supported between two adjacent beams, a bit, and a hollow extension

joint connecting the bit with the machine having provision whereby succeeding beams may be reached and bored and thereafter 10 serving as a continuous tube through the beams so that a wiring snake may be inserted therethrough.
